Term of patent 14 years

(Cl. D56—4)

FIG. 2

FIG. 1

FIG. 3

Figure 1 is a plan view of an escutcheon plate for a phonograph turntable, showing our new design with a control knob being shown in broken lines for illustrative purposes;

Figure 2 is a rear elevational view; and

Figure 3 is an enlarged sectional view taken on the line 3—3 of Figure 1.

The dominant features of our design reside in the portion shown in full lines.

We claim:

The ornamental design for an escutcheon plate for a phonograph turntable, as shown and described.
